(57) **CLAIM**

We claim the ornamental design for a financial cabinet apparatus for a gaming machine, as shown and described.

DESCRIPTION

FIG. 1 is a perspective view of a financial cabinet apparatus for a gaming machine showing our new design;
FIG. 2 is a right side elevation view of the cabinet apparatus, the left side being a mirror image thereof;
FIG. 3 is a front elevation view thereof;
FIG. 4 is a rear elevation view thereof;
FIG. 5 is a top plan view thereof; and,
FIG. 6 is a bottom plan view thereof.
